TREATING HYDROCARBONS

August Y. Mottlau, Elizabeth, N. J., assignor to
 Standard Oil Development Company, a corpora-
 tion of Delaware

No Drawing. Application April 29, 1938,
 Serial No. 205,000

11 Claims. (Cl. 196—13)

The present invention relates to an improved process for removing sulfur compounds from mineral oils. It is particularly concerned with the process of removing organically combined sulfur compounds from mineral oils, as for example, from petroleum hydrocarbons, with solvents of the class of aliphatic amino alcohols.

It is known in the art to remove sulfur compounds from petroleum oils by means of various solvents. It is also known to scrub gaseous mixtures with solvents, as for example, diaminopropanol, di amino diethyl ether and the like in order to remove the acidic gases, as for example, hydrogen sulfide and carbon dioxide from the same. However, I have now found that substances of the class of aliphatic amino alcohols, particularly the diaminopropanols, are desirable and improved solvents for the process of removing mercaptan sulfur from liquid hydrocarbons.

Suitable solvents of the present invention are selected from the class of aliphatic amino alcohols. The preferred amino alcohols are those containing from 3 to 6 carbon atoms in the molecule. Especially desirable solvents for the present invention are the amino propanols containing two amino groups and a primary hydroxy group. However, other diaminopropanols, as for example, 1-3-diaminopropanol-2, 1-3-diamino-2-methyl propanol-2 and 1-3-diamino-2-ethyl propanol-2, may also be used as well as aliphatic amino butanols and the like.

The process of the present invention of removing organic sulfur compounds from liquid mineral oils by means of solvents of the class of aliphatic amino alcohols may be carried out in any desirable manner. The process may be a countercurrent continuous treatment carried out in a tower containing suitable distributing and contacting means. The process may also be carried out in a single stage or in a multi-batch treatment in which the petroleum oil and the aliphatic amino alcohol are intimately mixed in any desirable manner.

The temperature and pressure of treatment may be varied over a wide range, depending upon the type of stock being desulfurized and depending also upon the particular organic sulfur compounds being removed. In general it is preferred to use atmospheric pressure and a temperature in the range from 60° to 85° F.

These aliphatic amino alcohol organic sulfur solvents may be used in order to extract or reduce the mercaptan sulfur content in any mineral oil. They are, however, particularly ef-

fective in reducing the mercaptan sulfur content of a petroleum mineral oil and thus may be readily and economically applied in the refining of petroleum hydrocarbons, as for example, naphtha, kerosene, Varsol, gas oil and the like.

5 The solvents of the present invention are particularly desirable for removing organic sulfur compounds from petroleum oils boiling in the range from 100° to 700° F. and especially from petroleum oils boiling in the range from 200° to 450° F.

10 The solvents of the present invention may be used in any manner desirable. It is, however, preferred to use an aqueous solution. The concentration will vary with the particular solvent being used, the stock being treated and type of organic sulfur compounds which are being removed. For example, in the treatment of a cracked or virgin naphtha with diaminopropanol, 15 it is preferred to use a concentration of diaminopropanol in the range from 40 to 60%.

20 The volume of the organic sulfur solvent used to treat a fixed volume of the oil being desulfurized will also vary, depending upon the character of the oil, the particular solvent being used and the character of the organic sulfur compounds being removed, as well as upon the concentration of the solvent in the aqueous solution and temperature of treatment. In general, it is preferred to use from one-half to one volume of aqueous solvent per volume of oil being desulfurized.

25 In order to more fully illustrate the invention, the following examples are given and are not to be construed as limiting the scope of the invention in any manner whatsoever.

EXAMPLE I

30 An East Texas virgin naphtha of about the following specifications:

Table 1

Gravity	°A. P. I.	62
Reid vapor pressure	pounds	7.0
Initial boiling point Engler	°F.	110
Per cent at 158° Engler		12.5
Final Engler		400

45 50 and containing 0.024% of sulfur was treated with an equal volume of an aqueous 40% solution of 1-3-diaminopropanol-1 at a temperature of about 70° F. After a single batch treatment the sulfur content on the treated naphtha was 0.016%. 55 The data may be summarized as follows:

Table 2

	Per cent	
Initial sulfur content of naphtha	0.024	100
Final sulfur content of naphtha	0.016	67
Sulfur reduction	0.008	33 5

EXAMPLE 2

A West Texas cracked naphtha of about the following specifications:

Table 3

Gravity	° A. P. I.	60
Reid vapor pressure	pounds	13.0
Initial boiling point Engler		110
Per cent at 158° Engler		25
Final Engler		400

and containing 0.209% of sulfur was treated in the manner described in Example 1 and the results may be summarized as follows:

Table 4

	Per cent	
Initial sulfur content of naphtha	0.209	100
Final sulfur content of naphtha	0.190	91
Sulfur reduction	0.019	9

EXAMPLE 3

A gasoline having about the following specifications:

Table 5

Initial boiling point Engler	110
Per cent off at 203	60
Final boiling point	320

and containing a total sulfur content of 0.495%, of which 0.480% was mercaptan sulfur and 0.015% was non-mercaptan sulfur, was treated in the following manner. The naphtha was extracted successfully five times with 30% by volume of an aqueous solution containing 60% diaminopropanol. The naphtha after these extractions was then washed in three successive treats with 30% by volume of pure water. The sulfur content of the treated naphtha was then determined and the results may be summarized as follows:

Table 6

	Total sulfur	Mercaptan sulfur	Non-mercaptan sulfur	Per cent total
Initial sulfur content of naphtha	0.495	0.480	0.015	100
Sulfur content of treated naphtha	0.165			31.3
Sulfur reduction of naphtha	0.330			68.7

EXAMPLE 4

In order to determine the effect of water alone, the above described naphtha was treated with 8 successive treats of water using 30% of water per volume of naphtha per treat. The results of this treatment may be summarized as follows:

Table 7

	Total sulfur	Mercaptan sulfur	Non-mercaptan sulfur	Per cent total
Initial sulfur content of naphtha	0.495	0.480	0.015	100
Sulfur content of treated naphtha	0.444			89.6
Sulfur reduction of naphtha	0.051			10.4

The above invention is not to be limited by any theory or any mode of operation, but only by the following claims in which it is desired to claim all novelty insofar as the prior art permits.

I claim:

1. Process for removing organic sulfur compounds of the mercaptan type from a mineral oil boiling in the range between 100 and 700° F. comprising treating the same at atmospheric pressure and at a temperature in the range from 60 to 85° F. with an aqueous solution of an aliphatic amino alcohol.

2. Process in accordance with claim 1 which said aliphatic amino alcohol contains from 3 to 6 carbon atoms in the molecule.

3. Process in accordance with claim 1 in which said aliphatic amino alcohol is diaminopropanol.

4. Process in accordance with claim 1 which said aliphatic amino alcohol is a diaminopropanol containing a primary hydroxy group.

5. Process for removing organic sulfur compounds of the mercaptan type from a petroleum oil boiling in the range from about 100 to 700° F. comprising treating the same at atmospheric pressure and at a temperature in the range from 60 to 85° F. with an aqueous solution of an aliphatic amino alcohol containing the latter in a concentration of 40 to 60%.

6. Process in accordance with claim 5 in which said aliphatic amino alcohol contains from 3 to 6 carbon atoms in the molecule.

7. Process in accordance with claim 5 in which said aliphatic amino alcohol is diaminopropanol.

8. Process in accordance with claim 5 in which said aliphatic amino alcohol is 1-3-diaminopropanol-1.

9. Process of removing organic sulfur compounds of the mercaptan type from a petroleum oil boiling in the range from 200° to 450° F. comprising treating the same with an equal volume of an aqueous solution of diaminopropanol having a concentration of 40 to 60% diaminopropanol.

10. Process for removing organic sulfur compounds of the mercaptan type from mineral oils boiling in the range between about 100° F. and 700° F. comprising treating the same in the liquid phase with an aqueous solution of an aliphatic amino alcohol.

11. Process in accordance with claim 10 in which said aliphatic amino alcohol is diaminopropanol.

AUGUST Y. MOTTLAU.
